UNITED STATES PATENT OFFICE.

MATHEW J. PHILIPSEN, OF DETROIT, MICHIGAN, ASSIGNOR OF ONE-HALF TO
H. L. HILLS, OF DETROIT, MICHIGAN.

WATER-TIGHT HINGE-JOINT.

1,247,715.

Specification of Letters Patent.

Patented Nov. 27, 1917.

Application filed February 19, 1917. Serial No. 149,641.

To all whom it may concern:

Be it known that I, MATHEW J. PHILIPSEN, a citizen of the United States, residing at Detroit, in the county of Wayne and State 5 of Michigan, have invented certain new and useful Improvements in Water-Tight Hinge-Joints, of which the following is a specification.

This invention relates to a hinge joint designed to be watertight and also to be so concealed when used in certain places that when in open position it will not show any marred or damaged surface.

The invention is adapted to a wide variety 15 of uses, which I have illustrated by showing the same used both as a hinge for automobile hoods and as a ridge cap or cover for roofs.

The invention consists in providing two 20 leaves, which may or may not be integral with the structure covered or united, which is bent both to form an angle along the adjoining margins of the leaves and also to increase the thickness of a portion of the margin, and in inclosing this angled and 25 thickened portion in a suitable casing.

In the accompanying drawings:

Figure 1 is a vertical sectional view through a portion of an automobile hood, with my invention applied thereto.

Fig. 2 is an enlarged transverse section through my hinge joint.

Fig. 3 is an end view.

Fig. 4 is a section on the line 4—4 of Fig. 3.

Fig. 5 is a plan view of the portion shown in Fig. 4.

Fig. 6 is a sectional view showing the hinge joint used as a ridge cap.

In these drawings 1 represents the hinge 40 leaf, which as shown in Fig. 1 is also a part of the hood top, and it will be understood that if applied to doors or to other forms of covers the door or lid may itself form a part of the hinge, being made integral with 45 one leaf when so desired.

Along one edge each leaf is bent over at right angles as at 2, and is then bent back on itself as at 3 thus increasing the thickness of the marginal portion, but the portions bent 50 back stop short of the body portions 1.

A semi-cylindrical casing 4 is formed having a length equal to the length of the marginal portions 2 and longitudinally slotted as at 5 along its flattened face 6.

At the ends of the casing the flattened 55 faces 6 are cut away as at 7, and into the ends of the casing are inserted blocks 8, after the bent portions 2 of the leaves are slipped into position along the slot 5. These blocks have a thickness substantially equal 60 to the cutout portions 7, and are provided with eccentrically placed pins 9.

The cut out portions 7 and the raising of the pin 9 slightly above or partially out of alignment with the flat face of the block permits 65 said pin to lie flush on one face with the leaves 1.

But this feature is optional and if desired said blocks may have the pins omitted and may be inserted into the ends of the casing 70 without cutting away any portion acting as stops for the bent portions of the leaves and to prevent exit of water. They are preferably secured by screws.

When used as a ridge cap the device is inverted as compared with its use on a hood, and of course is of greater length and size. In Fig. 5 I have shown its use on a roof 10. But the only change is in size and position, not in construction of any part of the joint. 75 It may be used wherever a joint of this character would be desirable, and when used on an automobile hood presents a neat appearance as no checked painted surface is exposed when the hood is opened and it is 80 also substantially water tight.

What I claim is:

1. A hinge joint comprising two leaves having bent marginal portions, and a slotted casing adapted to receive said portions. 90

2. A joint of the kind described comprising leaves having bent marginal portions, and a slotted casing receiving said bent portions, said portions working freely in the casing slot. 95

3. A joint of the kind described comprising two leaves, a longitudinally slotted case, means for closing the ends of the casing, pins carried by the end closures, and flanges on the leaves projecting into said slot and 100 working freely in said casing.

4. A joint comprising two leaves, a slotted casing, adjacent marginal portions of the leaves being bent and slidable in said slot, and retaining means placed in the 105 casing ends to check sliding movement of said bent portions.

5. A joint of the kind described compris-

ing leaves having bent and thickened marginal portions, and a longitudinally slotted casing adapted to receive said bent portions, the thickened portions having a thickness greater than the width of the slot.

6. A joint of the kind described comprising leaves having marginal portions bent at

an angle, said bent portions being bent back upon themselves, and a longitudinally slotted casing adapted to receive said bent marginal portions, as and for the purpose set forth.

In testimony whereof I affix my signature.

MATHEW J. PHILIPPSEN.
